[57] CLAIM

The ornamental design for a tape drive housing, as shown and described.

DESCRIPTION

FIG. 1 is a front elevation view of the tape drive housing;

FIG. 2 is a rear elevation view thereof;

FIG. 3 is a reduced right side elevation view thereof (left being mirror image);

FIG. 4 is a reduced top plan view thereof (bottom being mirror image);

FIG. 5 is a front elevation view of a second embodiment thereof wherein the only difference is in the front of the housing; and,

FIG. 6 is a front elevation view of a third embodiment thereof wherein the only difference is in the front of the housing.

FIG. 1

FIG. 2

FIG. 3

FIG. 4

FIG. 5

FIG. 6
